UNITED STATES PATENT OFFICE.

DWIGHT F. KILGOUR, OF LEXINGTON, MASSACHUSETTS.

BOILER.

1,321,755.

Specification of Letters Patent.

Patented Nov. 11, 1919.

Application filed May 19, 1916. Serial No. 98,655.

To all whom it may concern:

Be it known that I, DWIGHT F. KILGOUR, a citizen of the United States, and a resident of Lexington, in the county of Middlesex 5 and Commonwealth of Massachusetts, have invented an Improvement in Boilers, of which the following description, in connection with the accompanying drawings, is a specification, like characters on the drawings 10 representing like parts.

This invention relates to boilers and among other objects provides a boiler having a vertical barrel and a setting embodying certain features of the setting shown in 15 Letters Patent of the United States No. 909,805 granted to me January 12, 1909.

The setting disclosed in said patent is essentially long horizontally to allow sufficient space for the parts thereof which are necessary to produce its efficient burning of the 20 fuel, high heating effect, and substantial elimination of smoke.

The setting in said patent is shown applied to a horizontal barrel, but for some 25 uses the vertical barrel is preferable. The setting, however, is much longer than the diameter of the commercial vertical barrel, but by the present invention the said setting is adapted to the vertical barrel with the advantages thereof and certain other important 30 advantages hereinafter referred to.

The character of the invention may be best understood by reference to the following description of an embodiment thereof 35 shown in the accompanying drawings, wherein:—

Figure 1 is a side elevation of the illustrative boiler shown herein as embodying the invention;

Fig. 2 is a vertical, transverse section taken on line 2—2 of Fig. 5;

Fig. 3 is a front elevation of the setting and a portion of the barrel;

Fig. 4 is a rear elevation of the setting 45 and the barrel;

Fig. 5 is a vertical, longitudinal section taken on line 5—5 of Fig. 3;

Fig. 6 is a horizontal section taken on line 6—6 of Fig. 5; and

Fig. 7 is a vertical section taken on line 7—7 of Fig. 5.

Referring to the drawings, 1 designates a vertical barrel having upper and lower flue sheets 2 connected by flues 3 leading to an

upper chamber having a passage 5 for communicating with the usual stack (not shown).

To support the barrel it is provided with feet 7 (Figs. 1, 4, 5 and 7) adjacent its lower end resting upon horizontal beams 9 mounted on columns 11 (Figs. 4 and 6) conveniently of I-beam form. Thus I have provided a support for the vertical barrel which is entirely independent of the setting, so that the setting is not weakened by the expansion 55 and contraction of the boiler and the stability of the boiler support is not weakened by the effects of the fire on the setting.

The setting for the boiler comprises a double wall 13 of brick or other suitable 60 material beneath and preferably curved to conform to the contour of the barrel and presenting a chamber for distributing the products of combustion from the fire-box to the lower ends of the flues of the barrel as 65 more fully hereinafter described. Access to said chamber may be had through a rear door 14. Spaced side walls 15 project forwardly from the curved wall and contain 70 two of the columns 11 referred to. The side 75 walls are strengthened by vertical ribs 17 having their lower ends anchored in the foundation for the setting and their upper ends connected by tie-rods 19.

The crown of the fire-box comprises an 80 arch 21 (Fig. 2) of brick or other suitable 85 material having its ends supported by the side walls and strengthened by bars 23. The front wall 25 of the setting may be of brick or other suitable material covered by a plate 90 27 provided with fire doors 29 and ash pit doors 31.

Grate bars 33 are mounted on transverse 95 bars 35 supported by the side walls of the setting.

At the rear end of the grate bars is a bridge wall 37 having a vertical air duct 39 therein communicating at its upper end with twyars 43 and adapted to receive air through a perforated door 45 in one of the side walls.

At the rear of the bridge wall and spaced therefrom is a wall 47 extending from the crown to the bottom of the setting and provided at or near its bottom with an opening 100 communicating with a rearwardly extended combustion chamber 49. This chamber comprises side walls set in front of the main walls of the setting and is of a general horse-shoe

shape, flaring rearward and inclined slightly downward. The rear end of this combustion chamber communicates with the vertical chamber referred to leading to the flues 5 of the boiler. Preferably the combustion chamber extends a substantial distance into said vertical chamber as best indicated in Figs. 5 and 6.

Fuel fired on the grate gives off its products of combustion which flow rearward over the bridge wall as indicated by the arrows in Fig. 5 and encountering the wall 47 are deflected downward behind the bridge wall to or near the bottom of the setting thus 10 concentrating the products of combustion from the top to bottom of the setting or vertically. As the products of combustion pass the bridge wall they are mixed with the air and steam issuing from the twyers 43 and 15 pass into a mixing chamber 51 (Fig. 5) located behind the bridge wall at the entrance to said combustion chamber. The products of combustion pass from this chamber rearward through the combustion 20 chamber 49, which collects and draws in the products of combustion coming from the sides of the grate and concentrates the same laterally. The products of combustion thus become thoroughly mixed in said chamber 25 and the final combustion takes place therein as fully explained in said patent. The products of combustion pass from the combustion chamber into the chamber behind the same and are distributed thereby to the 30 flues of the boiler. They pass thence outward through the passage 5 to the stack.

The effect of the combustion in the combustion chamber is to heat the walls thereof to an intense and practically white heat of 35 incandescence effecting in actual practice practically complete combustion. Thus the products of combustion in passing from the grate rearwardly to the distributing chamber arrive at a high state of combustion 40 with an intense heat before they reach the entrance ends of the vertical flues in the barrel. Therefore in passing through said flues they are in a condition to produce their maximum water heating and steam-generating effect and pass outward from the 45 upper delivery ends of said flues at nearly all times in a perfectly transparent state and even at times of firing are only slightly discolored. The water level in the vertical 50 boiler is preferably a considerable distance below the upper tube sheet, thereby causing the upper portion of the flues to act as a superheater.

As stated, the setting is essentially substantially longer horizontally than the diameter of the barrel. Therefore the latter covers merely a part of the setting, leaving a substantial length of the latter projecting forwardly from said barrel. Next will be 60 described means for utilizing this portion

of the setting to increase the water and steam-generating capacity of the boiler and to protect the walls and crown of the firebox from the high heats therein. To accomplish this, a water delivery pipe 53 70 (Fig. 4) is connected to and communicates with the barrel adjacent the lower end thereof and extends downwardly therefrom to and communicates with a cross pipe 55, communicating in turn with vertical headers 57 75 at the rear end of the setting. These headers are connected with tubes 59 which extend forwardly through the walls of the setting beneath the barrel and have portions 61 exposed in the distributing chamber. 80 These tubes extend thence forwardly through the vertical wall 47 along the inner faces of the side walls of the fire-box to and through the front wall thereof, where they are connected with vertical headers 63. The 85 described circulatory system not only presents additional heating surface and protects the setting, but also prevents the formation of a scale on the bottom tube sheet by maintaining a rapid circulation of the 90 water and by providing in the lower ends of the header 57 a settlement chamber or mud drum which is removed from the direct heat of combustion and which is connected to the boiler by a connection which 95 is also removed from the direct heat of combustion. This arrangement prevents the formation of scale or mud deposit on the lower tube sheet, which usually causes rapid deterioration of this tube sheet by burning 100 of the metal.

The headers 57 and 63 may be provided with plugs 165 opposite the ends of said tubes and adapted to be removed to permit access to said tubes for convenience in assembly and repair thereof. The lower ends of the headers may be provided with pipes 167 having valves 169 and adapted to permit water to be drained from said headers as desired.

The headers 63 at the front of the setting are connected at their upper ends with a cross header 65 connected in turn with a series of tubes 67 which extend rearward beneath and adjacent the crown of the firebox toward the vertical wall 47. They curve thence upwardly through the crown of the setting and are connected with a horizontal header 69 (Fig. 3), communicating in turn with a pipe 71, leading upward to a point 115 substantially midway of the length of the boiler and connected by an elbow pipe 73 (Fig. 1) with said boiler. The horizontal headers 65 and 69 may be provided with plugs 75 and 77 respectively, opposite the 120 ends of the tubes 67, permitting access thereto for assembly, replacement or repair thereof. By passing at least one end of the tubes in the circulatory system through one 125 end of the setting and by supporting at least 130

one of the manifolds slidably, as on the projections from the front plate 27, the longitudinal expansion of the tubes is permitted, without buckling of the tubes.

5 The spaces between the horizontal runs of the tubes 67 beneath the crown of the setting may be closed by tiles 79 (Fig. 2) of fire clay or other suitable material resting thereon. These tiles will coöperate with 10 said tubes to protect the crown 21 of the setting from the fire in the fire-box in a highly desirable manner.

Water may be supplied to the boiler through a pipe 81 provided with a valve 83 15 and located a substantial distance up from the base of the boiler.

In use, water surrounding the flues in the boiler may flow downward through the pipe 53 and branch pipes 55 to the headers 57 20 and pass thence upwardly through the tubes 59 to the forward headers 63. During the initial portion of the circulation and before the water has passed into tubes surrounded by the products of combustion, the mud or 25 sediment in the water will settle in the bottom portions of the header 57 which constitutes one form of mud receiver or mud drum. In the course of its transit the water will be heated and transformed into steam

30 from the high heats in the walls of the distributing chamber and from the products of combustion passing from the grate along the side walls of the setting to the combustion chamber. The water and steam will pass 35 from the headers 63 upward into the horizontal header 65 and pass thence rearward again through the setting, beneath the crown of the fire-box, where it is further subjected to high heats, and passes thence 40 upward through the pipe 71 and elbow pipe 73 to the boiler delivering its steam above or adjacent the level of the water in the boiler. Thus by the arrangement of tubes described a circulation is maintained from

45 the boiler down through the setting, again through the setting, and thence upward to the barrel. The tubes not only desirably protect the sides and crown portion of the setting which are not covered by the barrel, 50 but also substantially increase the water capacity of the boiler and the percentage of the area of steam-generating surface to the grate area.

Having described one illustrative embodiment of the invention without limiting the 55 same thereto, what I claim as new and desire to secure by Letters Patent is:

1. In combination with a boiler having a circulatory system; an offset fire-box having 60 a top including a plurality of tubes forming a part of said circulatory system, the bottoms of said tubes being exposed to the fire, tiles carried by and above said tubes; and an air space between the top of said tiles 65 and the top of said fire-box.

2. The combination of a vertical fire tube boiler and its flues of a setting, an offset fire box, a combustion chamber, and a circulatory system, including a header having a supply connection at the rear of said setting, 70 a plurality of water tubes extending from said header to the front of said fire box and a mud receiving receptacle connected to said header and exterior to said combustion chamber. 75

3. The combination with a vertical fire tube boiler and its flues of a setting, including an offset fire box and a circulatory system, including a supply connection from the barrel of said boiler to a header; a plurality of horizontally disposed lateral tubes connected to said header and extending longitudinally of said fire box at one side thereof; a second header connecting the other end of said tubes; and a plurality of 80 horizontally disposed return tubes connected to said second header and passing through the upper portion of said fire box and connected to a return connection in the barrel of said boiler, said system conducting 85 water from said supply connection through said lateral tubes to said return tubes and thence through said return connection to said boiler.

4. In combination with a boiler having a 95 circulatory system; an offset fire-box having a top including a plurality of tubes forming a part of said circulatory system; tiles carried by said tubes; and an air space between the top of said tiles and the top of said 100 fire-box.

5. In combination with a fire tube boiler having a setting and an offset fire box; a circulatory system including a plurality of water tubes extending in a generally horizontal direction through both ends of said setting and said fire box and slidably relative to said setting and said fire box for 105 expansion independent thereof.

6. In combination with a boiler having a 110 circulatory system; an off-set fire-box having a top including a plurality of tubes forming a part of said circulatory system, the bottoms of said tubes being exposed to the fire, tiles carried by and above said 115 tubes; and an air space between the top of said tiles and the arch of said fire-box.

7. In combination with a boiler having a circulatory system; an off-set fire-box having a top including a plurality of tubes forming a part of said circulatory system; tiles carried by said tubes; and an air space between the top of said tiles and the arch of 120 said fire-box.

8. In combination with a vertical tubular 125 boiler having a barrel and a setting, including a fire-box at one side of said barrel; a circulatory system having a supply connection at the side of said barrel adjacent the bottom thereof; a manifold exterior to said 130

- setting and connected to said supply connection; side tubes extending from said manifold through said setting laterally of said fire-box; a second manifold at the other 5 end of said side tubes; top tubes connected to said second manifold and forming a portion of the top of said fire-box; and a return connection for carrying water from said top tubes back to said barrel.
- 10 9. A boiler comprising in combination, a vertical barrel and its flues, a setting therefor provided with a fire-box having a bridge wall, a wall at the rear of the latter leaving a mixing chamber between them, a combustion chamber of substantial length having an entrance end substantially narrower than said mixing chamber, a chamber beneath said barrel to distribute the products of combustion from said combustion chamber to said flues, steam-generating tubes in

said fire-box, and means connecting said tubes with said barrel.

10. A boiler comprising in combination, a vertical barrel 1 and its flues 3, a setting therefor provided with an offset fire-box 25 having a bridge wall 37, a wall 47 at the rear of said bridge wall leaving a mixing chamber between them, a combustion chamber 49 for receiving the products of combustion from said mixing chamber, a distributing chamber for delivering the products of combustion from said combustion chamber to said flues and a steam generating water circulating system connected to said barrel and protecting the walls and top 30 35 of said offset fire-box.

In testimony whereof I have signed my name to this specification.

DWIGHT F. KILGOUR.
